(57) **CLAIM**

I claim the ornamental design for a drinking cup, as shown and described.

DESCRIPTION

FIG. 1 is a perspective view of a drinking cup showing my new design;

FIG. 2 is a side elevation view thereof;

FIG. 3 is a top plan view thereof;

FIG. 4 is a bottom plan view thereof;

FIG. 5 is a sectional view thereof taken along line 5—5 in FIG. 3;

FIG. 6 is a perspective view of another embodiment of my design as shown in FIG. 1, with an added translucent band on the inner rim, said band having one or more insubstantial dimples on its' bottom edge;

FIG. 7 is a side elevation view thereof all other side views being identical;

FIG. 8 is a top plan view thereof;

FIG. 9 is a bottom plan view thereof; and,

FIG. 10 is a sectional view thereof taken along line 10—10 in FIG. 8.

The design is characterized by having three or less upright walls with a step in the outer wall and an inner chamber suspended by walls over a hollow bottom. Visibility of the interior walls may be reduced in subdued lighting depending on the amount of colorant used, but would be visible under bright overhead lighting.
